United States Patent Office

Des. 179,928
Patented Mar. 26, 1957

179,928

TEXTILE AWNING FABRIC OR SIMILAR ARTICLE

Rupert F. Beckstett, Bay Village, Ohio, assignor to The Astrup Company, Cleveland, Ohio, a corporation of Ohio

Application November 3, 1955, Serial No. 38,709

Term of patent 7 years

(Cl. D92—1)

Fig.1

Fig.2

Fig. 1 is a plan view of a textile awning fabric showing my new design, a unit of the design being set off by the dot and dash lines thereon; and

Fig. 2 is an enlarged detailed view thereof.

I claim:

The ornamental design for a textile awning fabric or similar article, substantially as shown.
